HOLDER FOR LIP STICKS OR COSMETIC STICKS

Ragnar Zeuthen Hanssen, Moss, Norway

Application October 27, 1934, Serial No. 750,341
In Germany October 28, 1933

9 Claims. (Cl. 206—56)

It is already known to construct holders for lip sticks or cosmetic sticks in such a manner that the stick is screwed out from or down into the holder by a rotation. The purpose is not only to feed forward the stick, when it has been worn, but also upon each use to screw down the stick into the holder to protect it against heat, deformation and soiling of the habit and of the hands in case the cover might fall off unintentionally. However, experience shows that the screwing-down of the stick is frequently forgotten, because it requires an operation other than putting on the cover.

According to the present invention the screwing device and the cover are so designed that the putting on of the cover must necessarily be connected with such a rotation that the stick is thereby screwed down into protected position, and the return rotation necessary to remove the cover causes the screwing-out of the stick into position for use. In this manner at each putting-on of the cover the stick is brought automatically into the position most favorable to its conservation, so that its screwing-down into the holder cannot be forgotten. The holder may also be so made that at each removal of the cover the stick is fed forward automatically an amount corresponding to the degree of wear which has taken place each time.

An embodiment of the invention is illustrated in the annexed drawings. Fig. 1 shows one half of an axial longitudinal cross section of the holder with stick on the line 1—1 of Fig. 4. Fig. 2 shows a similar axial section on the line 2—2 of Fig. 4. Fig. 3 shows a partial section on the line 3—3 of Fig. 4. Fig. 4 shows a developed view of the lower portion of the cover lining and of the inner cover sleeve. Fig. 5 shows an elevation of the stick holder after removal of the cover, some parts being broken away to show parts otherwise not visible. Fig. 6 shows an elevation of the cover proper, the most part of the exterior cover member 1 and some portion of the cover lining 11 being broken away.

In Fig. 4 the lining 11 of the cover 1 is shown in full lines and the sleeve 14 in dotted lines.

The lip stick is movable longitudinally in ordinary manner in an exterior holder in the form of a cylinder 2, the stick at its lower end being attached in a ring 3 having an exterior pin 4 which projects into a steep helical groove 5 on the interior side of the cylinder 2. The pin projects through an axial longitudinal guide of a turnable interior sleeve 6. By turning the sleeve 55 in one, or the other direction the lip stick is

moved preferably through about the stroke h (Fig. 1) upon rotating the sleeve 6 through about $\frac{1}{5}$ of a complete revolution. This arrangement is well known.

According to the invention the sleeve 6 may be coupled to the cover 1 to enable the stick being screwed by means of the cover. For this purpose the sleeve 6 is bent outwards at 6a and downwards at 6b and provided with pressed edge teeth 8 cooperating with teeth 9 made in the lower edge of inwardly bent lugs 10 of a lining 11 which is fixedly connected to the cover. The cover lining has one or more bayonet grooves consisting of an axial portion 12 and a peripheral portion 12a.

The length of the groove portion 12a corresponds just to the stroke h and limits the turning movement of the cover 1 in one direction relatively to the cylinder 2 by means of a pin 13 attached therein and meshing with the groove portion 12a. The bayonet groove has further on the side opposite the portion 12a a short peripheral extension 12b joining to the portion 12 through an inclined portion 12c.

When the cover 1 is put on, its groove portion 12 moves axially over the pin 13 downwardly until the top edge of the groove portion 12a strikes against the pin. Then the cover is turned to the left (arrow 20, Fig. 4) to fixed position, until the bottom of the groove portion 12a stops against the pin 13. This rotation is transmitted by the teeth 9, 8 to the sleeve 6b, 6a, 6, pin 4 and ring 3 on to the lip stick 1 which owing to the helical groove 5 is withdrawn into the cylinder 2 (inner position). By an opposite rotation of the cover 1 to the right the pin 13 moves firstly in the groove portion 12a to a position directly above the axial groove portion 12, whereby the stick 1 is moved through the same stroke h outwards, but owing to the additional groove portion 12b the cover may be further rotated to the left, until the left hand groove portion 12b strikes against the pin 13. By this additional rotation the stick 1 is fed forward through a certain amount. If then the cover is removed, it is firstly moved somewhat axially, until the inclination 12c strikes against the pin 13. But then the coupling teeth 9, 8 have been separated from one another. During a further axial movement of the cover the inclination 12c slides relatively to the pin 13 which imparts to the cover a small forward rotation, however, now without rotating the sleeve 6 along with it. Then the pin finally arrives into the axial groove portion 12 and permits the complete removal of the cover.

50
55

- As will be seen, when the stick 1 is to be used and the cover 7 is therefore rotated back (released), always a greater rotation takes place than at putting on the cover and effecting the forward rotation (locking rotation) of the cover. Therefore the stick 1 is always fed forwards through an amount which is as much greater than the stroke h as corresponds to the additional groove 12b.
- However, in order to obtain automatically a forward feed of the stick corresponding to the wear which has taken place each time, the following special arrangement may be used: Inside the cover 7 there is a stick contacting sleeve 14 forming a sort of interior cover and being slideable longitudinally and also rotatable relatively to the cover 7. At the top a combined compression and torsion spring 15 is inserted between members 7 and 14. The sleeve 14 has at one or more places stamped out in it a lug 16 with a transverse tooth row 17 projecting into an opening 18 of the lining 11 and located opposite a similar tooth row 19 in the top edge of the opening 18 but normally spaced so much therefrom axially as the above-mentioned special stick movement corresponding to the groove extension 12b. The spring 15 tends to so move the sleeve 14 that the lug 16 is located at bottom and to the right in the opening 18 (Fig. 4).
- Now, the sleeve 14 has at its bottom portion an open recess 19a, 19b, 19c of the same axial height as the groove 12 and of the same peripheral width (between 19a and 19c) as the groove 12a of the cover lining 11, however having no extension corresponding to 12b. In case the transverse tooth rows 17 and 19 have the same relative location as shown in Fig. 4, the grooves 12, 12a are located as shown relatively to the recess 19a, 19b, 19c.
- This location is occupied by the member 7 relatively to the member 14, when the cover is removed, the spring 15 pressing the lug 16 against the bottom and the right hand side of the opening 18. As shown in Fig. 1 the stick 1 projects the normal amount for use out from the cylinder 2.
- If now the cover 7, 14 is put on, so that the groove 12 embraces the pin 13, the stick point lifts the sleeve 14 to the position of Fig. 1 in compressing the spring 15, whereby the tooth row 17 of the lug 16 enters in engagement with the tooth row 19 of the cover 7, 11 to connect the member 7 with the member 14 non-turnably. The top edge of the groove 12a and that of the recess edge 19b are in contact with the pin 13.
- Now the cover 7, 14 is so turned in the arrow direction into locking position that the right hand end of the groove 12a strikes against the pin 13 and the stick is thereby lowered just through the stroke h into protected position.
- If the stick is to be used, the cover 7, 14 is released by being rotated opposite the arrow direction 20, until the edge 19a contacts with the pin 13, the stick 1 being thereby raised again and the cover may be removed.
- But when the stick 1 has been somewhat worn owing to use and the cover 7, 14 is then put on, the stick point now projecting correspondingly less upward will not raise the sleeve 14 so much relatively to the cover member 7, 11, whereby between the tooth rows 17 and 19 there will exist an axial distance exactly corresponding to the degree of wear of the stick, the members 7 and 11 being therefore not any more coupled to the sleeve 14.
- Then, the cover 7, 14, after having been locked

(in arrow direction 20), is again released (opposite arrow direction 20), whereby the edge 19a strikes firstly against the pin 13 and prevents a further rotation of the sleeve 14, but the cover 7, 11 may be turned forth, the stick 1 and the sleeve 14 with lug 16 being thereby further raised, until the tooth rows 17 and 19 engage one another, and only then the further rotation is stopped. The pin 13 now projects into the extension 12b to a degree corresponding to the degree to which the stick 1 has been worn. Consequently the stick has been fed forward through the correct amount. Then the cover may again be removed, whereby the spring 15 restores the relative location of the members 7, 11 and 14.

In this manner an automatic forward feeding of the stick is always obtained which corresponds to the actual wear.

Obviously the recess edge 19c may be shaped in any manner and may also be cut away, because that edge has no function. Also the size of the extension 12b is unimportant provided it is at least equal to the peripheral movement corresponding to the greatest distance between the tooth rows 17 and 19 in Fig. 4.

I claim:—

1. Holder for lip sticks, cosmetic sticks or the like, comprising screwing means operating during a rotation to move the stick out from or down into the holder, locking means for the cover operating to lock by a rotation of the cover in one direction and to release by a rotation in opposite direction, and means for so coupling together the screwing means and the locking means that the stick must be screwed inwards during a rotation of the cover in locking direction and outwards during a rotation of the cover in releasing direction.

2. Holder according to claim 1, wherein the locking means consist of a bayonet groove cooperating with a pin, one of these members being arranged in connection with the cover and the other one in connection with the holder proper, said groove being so designed that the angle of rotation of the cover for release is somewhat greater than that for locking, and means for utilizing the difference in said angles to feed forward the stick upon its having been worn.

3. Holder according to claim 1, wherein the locking means consist of a bayonet groove cooperating with a pin, one of these members being arranged in connection with the cover and the other one in connection with the holder proper, said groove having an axial portion and a peripheral portion, the latter having an extension on the side opposite the axial portion, said extension having a greater axial size than that of the coupling means between cover and the screwing means.

4. Holder according to claim 1, wherein the locking means consist of a bayonet groove cooperating with a pin, one of these members being arranged in connection with the cover and the other one in connection with the holder proper, said groove having an axial portion and a peripheral portion, the latter having an extension on the side opposite the axial portion, said extension having a greater axial size than that of the coupling means between cover and the screwing means, the groove extension being provided with an inclined edge joining to the edge of the axial portion.

5. Holder according to claim 1, wherein the cover is provided with an internal spring-pressed sleeve movable axially and rotatably relatively to

the cover, means on the sleeve to stop the rotation of the cover in its position on the holder, as soon as the stick moving outwards during such rotation has arrived to its correct position in the holder and has lifted the sleeve into stopping position against the spring action.

5. Holder according to claim 1, wherein the cover is provided with an internal spring-pressed sleeve movable axially and rotatably relatively to the cover, the sleeve and the cover having each a peripheral tooth row located cooperatively opposite one another so as to stop the rotation of the cover in its position on the holder, as soon as the stick moving outwards during such rotation has arrived to its correct position in the holder and has lifted the sleeve into stopping position against the spring action.

6. Holder according to claim 1, wherein the locking means consist of a bayonet groove cooperating with a pin, one of these members being arranged in connection with the cover and the other one in connection with the holder proper, said groove having an axial portion and a peripheral portion, the latter having an extension on the side opposite the axial portion, said extension having a greater axial size than that of the coupling means between cover and the screwing means, said cover having an axially movable and rotatable spring-pressed sleeve, means on the sleeve to stop the rotation of the cover in its position on the holder, as soon as the stick moving outwards during such rotation has arrived to its correct position in the holder and has lifted the sleeve into stopping position against the spring action.

7. Holder according to claim 1, wherein the locking means consist of a bayonet groove cooperating with a pin, one of these members being arranged in connection with the cover and the other one in connection with the holder proper, said groove having an axial portion and a peripheral portion, the latter having an extension on the side opposite the axial portion, said extension having a greater axial size than that of the coupling means between cover and the screwing means, said cover having an axially movable and rotatable spring-pressed sleeve, means on the

other one in connection with the holder proper, said groove having an axial portion and a peripheral portion, the latter having an extension on the side opposite the axial portion, said extension having a greater axial size than that of the coupling means between cover and the screwing means, said cover having an axially movable and rotatable spring-pressed sleeve, the sleeve and the cover having each a peripheral tooth row located cooperatively opposite one another so as to stop the rotation of the cover in its position on the holder, as soon as the stick moving outwards during such rotation has arrived to its correct position in the holder and has lifted the sleeve into stopping position against the spring action.

8. Holder according to claim 1, wherein the locking means consist of a bayonet groove cooperating with a pin, one of these members being arranged in connection with the cover and the other one in connection with the holder proper, said groove having an axial portion and a peripheral portion, the latter having an extension on the side opposite the axial portion, said extension having a greater axial size than that of the coupling means between cover and the screwing means, said cover having an axially movable and rotatable spring-pressed sleeve, the sleeve and the cover having each a peripheral tooth row located cooperatively opposite one another so as to stop the rotation of the cover in its position on the holder, as soon as the stick moving outwards during such rotation has arrived to its correct position in the holder and has lifted the sleeve into stopping position against the spring action, the sleeve being provided with an open recess with a height and a width corresponding to the bayonet groove.

RAGNAR ZEUTHEN HANSSEN.
